(No Model.)

E. O. CHASE.

MACHINE FOR SHAVING PRINTERS' LEADS.

No. 416,568.

Patented Dec. 3, 1889.

UNITED STATES PATENT OFFICE.

EDWARD O. CHASE, OF NEWARK, NEW JERSEY, ASSIGNOR TO FARMER, LITTLE & CO., OF NEW YORK, N. Y.

MACHINE FOR SHAVING PRINTERS' LEADS.

SPECIFICATION forming part of Letters Patent No. 416,568, dated December 3, 1889.

Application filed October 19, 1886. Serial No. 216,675. (No model.)

To all whom it may concern:

Be it known that I, EDWARD O. CHASE, of Newark, Essex county, New Jersey, assignor to FARMER, LITTLE & CO., of New York, N. Y., have invented an Improved Machine for Shaving and Dressing Printers' Leads and Brass Rules; and I do declare the following to be a full, clear, and correct description of my invention, reference being had to the accompanying drawings, making part of this specification, and to the letters of reference marked thereon, in which—

Figure 1 is a side elevation showing chain in dotted lines. Fig. 2 is a plan view of my invention. Fig. 3 is a vertical section taken through line *a a*, showing the knives as open. Fig. 4 is a vertical section taken through line *b b* for the purpose of showing the wheels over which the chain passes, also part of mechanism for regulating the knives. Fig. 5 is a longitudinal view of gripping device, partly in section.

In the drawings like parts of the invention are designated by the same letters of reference.

The nature of the present invention relates to certain improvements, as fully set forth in the lead-shaving machine for which Letters Patent were granted Alfred Nielson March 26, 1874.

To enable those skilled in the art to make and use my invention, I will describe the same.

A is a frame-work for supporting the operative parts of the machine, the upper portion *B* being made open to allow the nipper-carriage *P* to pass through the same. Upon the inside of this upper portion *B* are placed the toothed wheels *C C²*, two directly in advance of the shaving-knives and two near the rear end of the machine and in line with each other. Over these wheels *C* and *C²* and engaging with the same is passed an endless chain *D*. The forward wheels *C* are supported upon the shafts *E*, having their bearings in boxes in the upper portion *B* of the frame, and upon the outer ends of these shafts *E* are secured the cog-wheels *F*, engaging with the pinions *G*, held upon a driving-shaft *H*, having its bearing in boxes directly below the shafts *E*. The rear wheels *C²* are

held upon shafts *I*, having their bearing in the boxes *J*, formed by continuing the metal in the manufacture of the side plates *L*. The side plates are provided with oblong slots *M*, through which are passed the bolts *N²*, and also with the end screw-bolts *O*.

By employing the slotted plates *L* and adjusting the same the position of the wheels *C²* to the chain *D* is varied, as may be necessary to govern the tension of the chain *D*.

The rear screws *O* have their bearings upon the rear end of the upper portion *B*, and assist in holding the side plates *L* in position.

P shows the nipper-carriage of the machine free to move to and fro through the machine. This consists of a plate of metal planed true upon its side and provided with the lips extending at right angles to the sides of the same, which lips bear upon the upper face of the raised portion *B* of the frame *A*, and the lower projecting front portion constituting the lower stationary jaw *Q*. Back of this forward portion *Q* of the plate the metal is continued to form ears *g*, within which is swiveled or hung the upper nipper or jaw *R*. This upper nipper or jaw *R* forms a continuation of a rod *S*, passed through the plate *P*, over which is passed a collar *T*, provided with the trunnions *t* on each side, 80 which trunnions *t* are attached to the chain *D*.

Between the movable jaw *R* and the stationary one *Q* is a movable tongue *U*, attached to the forward end of a rod *V*, passing through the rear end of the plate *P*, and over which is placed a spiral spring *v*. This rod is headed, as at *W*, and when the carriage *P* has reached the extent of its movement from the front to the rear of the machine this head *W* meets and is brought into contact with a round-headed rod *X*, free to move in the barrel *Y*, supported upon an upright *Z*, secured upon the rear of the upper portion *B* of frame *A* and so positioned that the headed rod *X* is in line with the headed rod *V*. The rod *X* has passed over it a spring.

Secured to the gripper-carriage is a strip 2, of leather or other flexible material. This strip extends downward and over the roller 1, the lower end being loose, as shown in Fig. 1.

3 shows an elongated curved lever free to

move upon a bolt 4, passed through it about centrally, which bolt enters the upper portion B of the frame A. This curved lever 3 is provided at its rear end with a raised projection 5, and its forward end is connected to a short swinging plate 6, moving on a bolt 6^x passed through its rear end slightly in advance of the point of its connection with the curved lever 3, and entering the portion B of the frame A.

To the lever 3, on its under side, and near its point of connection with the plate 6, is attached a rack 7, engaging with a partially-toothed wheel 8, secured upon the rear end 15 of a rod 9, free to turn in the circular boxes 10, attached to the upper portion B, upon one side of it.

At the forward end of the plate 6 is a standard 11, supporting one end of a curved plate 12, the opposite end of which, through a link 13, is connected to the toggles 14, constituting the toggle-joint, by which the upper dressing or finishing knife is operated.

The forward end of the rod 9 is connected 25 by a crank-arm 14² and rod to the plate 15, intended to carry one of the side knives or cutters for shaving or dressing the sides of the lead or rule. This plate 15 extends across the face or front of head 21, in which are received the upper 17 and under 18 dressing or finishing knives or cutters. The opposite end 30 of the plate 15 is connected to the movable plate 19, the forward end of which is extended and forms the opposite shaving or dressing 35 knife by means of a link 26.

The knife 30 used with the plate 15 is inclined and its position relatively to the side of the lead or rule to be operated upon is regulated by a screw 20, passed through an eye on 40 the upper end of the knife and having its bearing against a shoulder on the upper end of the plate 15.

The head 21 for supporting the upper and lower dressing-surfaces 17 and 18 is bolted to 45 the portion B of the frame A in advance of the wheels C. It is provided with an opening to admit of the introduction of the ends of the leads or rules to be dressed. Fitted snugly but free to move in it is the upper 50 cutting or shaving surface 17, the position of which to the lower cutting-surface 18 is regulated by the screw 22 engaging with the upper portion of the cutting-surface 17, and to the rear of this surface are attached the ends 55 of the toggles 14.

Directly at the base of the head 21, in an extension forming a front lip 23, is positioned the lower cutting-surface 18, held, when its position has been regulated by set-screws 24, 60 to the lower position of the head 21.

A V-shaped block 25 is used in connection with the nipper-carriage P, and on the rear movement of this carriage impinges upon the raised projection 5 upon the curved lever 3, 65 imparting movement to the opposite end of the lever, and through the rack 7, partially-toothed wheel 8, and plate 6, connected to the

toggles 14, as described, moving the upper cutting-surface 17 upward, and by connection, as described, with the plate 15, in which is held one of the side knives, causing the same to be thrown out and the opposite knife or cutter, attached, as shown, to it, thrown in.

It will be observed that the upward movement of the cutting-surface 17 is caused by 75 the shortening of the toggles 14, as the same are drawn back through the operation described.

Such being the construction, its operation will be readily understood. The upper cutting-surface 17 is adjusted by means of the screw 22 to the lower cutting-surface 18, and both to the thickness of the lead or brass rule to be operated upon. The side knives or cutters are adjusted to the width of the lead or rule 80 to be operated upon by the screw 20, and the opposite knife or cutter is brought into the proper position by moving forward or backward the block or plate 19, and is then connected to the plate 15 by means of the link 26. 90 The lead or rule to be dressed is then introduced into the machine through the opening in the head 21, its forward end projecting a short distance beyond or in advance of the cutting-surfaces. Motion is now communicated to the driving-shaft through power applied to the same. This in turn, through the pinions and cog-wheels, gives motion to the wheels C and chain D. As the same starts, the upper nipper, which has been open, is 100 closed upon the lead or rule and lower nipper by or through the movement of the collar attached by the trunnions t to the chain D as the same—the collar—passes over the wheels C, and moves upward upon the rod S of the upper nipper, and the lead or rule is drawn through the upper and lower cutting-surfaces and between the side knives as the motion is continued, and thus has its upper and lower 105 surfaces and sides simultaneously shaved or 110 dressed by contact of the shaving or dressing tools with the same. The motion of the machine continuing, the chain is drawn along, carrying with it the shaved lead or rule until the collar T, attached to the chain D, reaches 115 the wheels C². As the collar T passes over and underneath the same, it moves down upon the rod S of the upper nipper, and as the same is moved through the collar T from the vertical into an inclined position the upper nipper is 120 raised and releases its bite upon the lead or rule. A short time before the opening of the upper nipper, as just described, the rear end of the rod V, carrying the tongue, is brought into contact with the forward end of the rod 125 X, free to move in the barrel Y, and the spring x upon the same has been compressed. With the opening of the upper nipper R the tongue U, through the expansion of this spring x and the forward movements of the 130 rods V and X, has a forward movement imparted to it, and ejects the shaved lead or rule out from its position between the nippers into the receptacle 2. At the next forward move-

ment of the carriage the ejected lead is carried forward on the strip or receptacle 2 and is discharged through the spout A². The expansion of the spring v restores the rod V to its normal position. During the operations of opening the upper nipper and ejecting the shaved lead or rule the V-shaped block 25 has impinged upon the raised projection 5 of the lever 3 and imparted movement to the 10 same, and through this movement this lever, connected, as already shown, to the upper cutting-surfaces as well as the side knives, has caused these surfaces, the upper one to be moved up in the head 21 and one of the side 15 knives outward and the opposite side knife inward. The motion of the machine continuing, the nipper-carriage P is returned to its original position, the cutting-surfaces restored to their original position through the 20 impingement of the V-shaped block 25 upon the V-shaped block 27, in connection with the plate 6, rack 7, partially-toothed pinion 8, and rod 9, already described, and the upper nipper having been closed upon the end of a lead 25 or rule introduced, as already described, the operations are repeated.

On the upper face of the portion B, on the side opposite to that on which the lever 3 is located, is pivotally mounted a short horizontal lever 3^X, the forward end of which is provided with an adjusting-screw, bearing against

the portion B, while the rear end bears against the side of the nipper, so as to steady it during the operation of opening the jaws.

Having now described my invention, what I claim as new is—

1. In combination with the stationary and movable nippers, the tongue U upon the rod V, the spiral spring v, and the rod X, free to move in the barrel Y and provided with a 40 spiral spring x, when the same shall be constructed and operated substantially as and for the purpose set forth.

2. The combination, with the chain D and nipper-carriage P, provided with the movable 45 nipper R, of the receptacle 2, in which the shaved or dressed leads or rules are received after ejection from the nipper-carriage P, substantially as and for the purpose specified.

3. The combination, with the curved lever 50 3, of the V-shaped blocks 25 27, rack 7, partially-toothed wheel 8, rod 9, plate 6, provided with the curved plate 12, crank-arm 13, toggles 14, and upper cutting-surface 17, crank 14², plate 15, side knife 30, movable plate 19, 55 and link 26, substantially as and for the purpose specified.

EDWARD O. CHASE.

In presence of—

W.M. O. BARMAY,
WILLIAM V. H. HICKS.
